UNITED STATES PATENT OFFICE.

CHRISTOPHER F. SCHLEMMMA, OF PRESTON, IOWA.

LIFTING-JACK.

1,114,918.

Specification of Letters Patent. Patented Oct. 27, 1914.

Application filed August 5, 1913. Serial No. 783,130.

To all whom it may concern:

Be it known that I, CHRISTOPHER F. SCHLEMMMA, a citizen of the United States, residing at Preston, in the county of Jackson 5 and State of Iowa, have invented certain new and useful Improvements in Lifting-Jacks, of which the following is a specification.

My invention relates to lifting jacks with 10 special reference to raising and lowering water pipes in and out of wells, and the object is to provide simple means whereby a pipe may be easily lowered into and removed out of very deep wells, in a limited space of 15 time by a single operator without an assistant.

The following specification will definitely disclose how my device is constructed and operated when read in connection with the 20 drawings accompanying the same and forming a part hereof.

Figure 1 is a perspective view of my machine taken from one side. Fig. 2 is a perspective view taken from the opposite side 25 of Fig. 1 and holding a pipe partly drawn out of a well. Fig. 3 is a perspective view of one of the sprocket wheels with attachments.

Like characters of reference denote corresponding parts in each of the figures.

Referring to the drawings, the frame consists of two metal bars 2 which are united together at the base by a cross bar 4. A short distance above the base is journaled a shaft 8 upon which is mounted a gear wheel 35 10 and a drum 12. Above the shaft 8 is journaled another shaft 14 upon which is mounted a small gear wheel 15 which meshes in with the gear wheel 10. Upon the other end of the shaft 14 and outside of the frame is 40 mounted a sprocket wheel 16 which is adapted to be detached from the shaft when transporting the machine. The gear wheels 15 and 16 are rigidly mounted upon the shaft 14, but the shaft is loosely journaled in the 45 frame and is adapted to have an endwise movement in a horizontal plane, whereby the gears 15 and 10 are brought into and out of engagement with each other. To accomplish the horizontal movement of the shaft 50 with the gears thereon, there is attached to the frame above the shaft a cross bar 18 and to this is pivoted a lever 20 having an arm 22 which arm is bifurcated at its lower end 24 and encompasses the shaft between 55 the gear 15 and a collar 25 which collar is rigidly secured to the shaft 14. It will be

seen by raising and lowering the lever 20 that the gear 15 is brought out of and into engagement with the wheel 10. To lock the wheels 10 and 15 when in engagement with each other, there is provided a dog 26 that is pivoted to the cross bar 18 and adapted to be brought into engagement between the teeth of the gear wheel 15.

At the upper end of the frame the two 60 bars 2 composing the frame are rigidly secured to a block 30 in which block is a shaft 32 and on which is mounted a wheel 34 in a slot 33 in said block. Around this wheel 34 runs a cable 35 which is provided with a hook 36 at one end and at the other end is secured to the drum 12 near the wheel 10, and arranged to be wound upon one end of the drum in one direction. In the lower corner of the block 30 is pivoted another 65 wheel 38 over which a cord 39 is arranged to travel. One end of the cord is attached to and wound around the drum 12 in the opposite direction from the winding of the cable 35 so that when the cable is wound upon the 70 drum the cord is unwound and when the cord is wound upon the drum the cable is unwound. To the other end of this cord 39 is secured a handle 40. Through the block 75 30 and the frame bars 2 is mounted a shaft 42, which is braced by stays 44 and on the outer end of said shaft is detachably mounted a wheel 45. Around the sprocket wheel 45 and the sprocket wheel 16 travels an endless chain 46. Against the sides of the block 80 90 and frame at or near the top are secured bracket arms 50 and 51, one on each side and to the arm 51 is pivoted a cross bar 52 which is adapted to rest upon the arm 50. The arm 50 is bent up at the outer end to prevent the 95 cross bar 52 from becoming disengaged.

The manner of using this device is substantially as follows:—Starting with the pipe A to be withdrawn from the well, the operator lifts the lever 20 bringing the gear 10 out of mesh with the gear 15 and draws down the cord 35 to the top of the pipe A and fastens it around the pipe by the hook 36. He then operates the lever 20 bringing the gear 15 into mesh with the gear wheel 10 and grasping the sprocket chain 46, draws up the pipe to the position shown in Fig. 2 with the upper end back of the cross bar 52. Then he secures the lower length B of the pipe so that it will not drop down into the 110 well and uncouples the upper length A from the coupling D and lifts up the cross piece 52.

which allows the pipe A to be brought out from resting against the block and frame, and then disengages the wheel 15 from its engagement with the wheel 10 and that allows the pipe A to be lowered to the ground.

In order to lower the hook 36 quickly after the gear wheel 15 has been disengaged from the wheel 10, the operator takes hold of the hook and pulls it down and at the same time 10 this winds up the cord 39 on the opposite side of the drum. When it is desired to draw up the hook into position so that it may be engaged with the next pipe, he takes hold of the handle 40 and as he pulls on that, he 15 raises the hook without taking hold of the sprocket chain 46. After the hook has been brought into engagement with the next piece of pipe by operating the lever 20 it brings the gear wheel 15 into engagement with the gear wheel 10 and then the operator grasps 20 the chain and raises the next length of pipe to the position shown in Fig. 2.

It will be seen by this mode of construction and operation of these different parts 25 that the operator has always every feature of lifting the pipes or lowering them quickly or holding them in any given position entirely at his command and if the pipe be partly out and anything is wrong, he 30 can move the dog 26 into engagement with one of the cogs on the gear wheel 15 and lock both the gears 15 and 10 and hold the pipe in any given position. Further this 35 can be operated quickly and without the aid of the usual assistance as all the parts are within reach of the operator and does not require any particular expert to operate it. It will be noticed that by means of this 40 construction, the pipe as it is removed from the well will assume nearly a vertical position at all times and is held from tipping in either direction by the guard 52 and can 45 easily be released by disengaging the cross bar 52 from the bracket hook 50.

I understand that derricks and hoisting 50 machines are not new, but the manner of construction, mode of application and operation, the additions and features I employ whereby a single person can operate it quickly and with little strength I believe are new.

Having now described my invention what I claim is:—

1. In a device of the character described, 55 a frame, a shaft in the lower part of the frame having a gear wheel mounted thereon, a drum mounted on said shaft, a pulley pivoted in the upper part of the frame, a cable provided with a hook at one end and 60 attached to the drum at the other end and adapted to travel over the pulley, means engaging the gear wheel on the shaft for winding the cable on the drum and raising the pipe from the well, and means including 65 a guard secured to the frame for holding

the pipe in an upright position when the pipe is partly drawn from the well or lowered into the well.

2. In a device of the character described, 70 a frame, a shaft journaled in the lower end of the frame, a gear wheel mounted upon the shaft, a drum on the shaft, a second shaft loosely journaled in the frame and adapted to be moved endwise in the frame, 75 a gear mounted on said shaft, means for bringing said gear into and out of engagement with the gear wheel on the first shaft, a pulley mounted in the frame near the top, a single cable secured to the drum and arranged to be wound on the drum in one direction and to travel over said pulley, a second pulley mounted in the frame near the top, a cord attached to the drum and arranged to be wound on the drum in the opposite direction from that of the cable, 80 means for rotating the drum to wind the cable and cord in opposite directions on the drum, and means for grasping the load to be raised.

3. In a device of the character described, 90 a frame, a shaft journaled near the bottom of the frame and carrying a gear wheel, a drum mounted on said shaft, a second shaft loosely journaled in the frame at a short distance above the first shaft and carrying 95 a gear adapted to engage the gear wheel on the first shaft, a sprocket wheel mounted on said second shaft, a shaft journaled near the top of the frame, a sprocket wheel mounted on said upper shaft, a sprocket chain traveling around the two sprocket wheels, a pulley mounted in the top of the frame, and a cable secured to one side of the drum and adapted to travel over the pulley and engage the load to be lifted.

4. In a device of the character described, 105 a frame, a shaft journaled in the frame near the bottom and carrying a gear wheel and a drum, a second shaft loosely journaled in said frame and carrying a gear wheel adapted to mesh in with the gear wheel on the first shaft, a sprocket wheel on said second shaft, means for bringing the gear wheels on the two shafts into and out of engagement with each other, a shaft journaled in the upper part of the frame and carrying a sprocket wheel, a sprocket chain arranged to travel around both sprocket wheels, a pulley journaled near the top of the frame, and a cable secured to the drum and arranged to travel over the pulley and provided with means for grasping the load.

5. In a device of the character described, 115 a frame, a shaft journaled near the bottom of the frame on which is mounted a gear wheel and a drum, a second shaft loosely journaled in the frame and carrying a gear wheel adapted to engage the gear wheel on the first shaft, a sprocket wheel on said second shaft outside of the frame, means for 120

130

bringing the gear wheels on both of the shafts into and out of engagement with each other, a shaft journaled in the upper end of the frame and carrying a sprocket 5 wheel, a sprocket chain arranged to travel around both sprocket wheels, a pulley pivoted in the upper end of the frame, a cable attached to and wound around the drum in one direction and arranged to travel over 10 the pulley, a second pulley in the frame, a cord secured to and wound upon said drum

in the opposite direction from that of the cable and arranged to travel around the second pulley, whereby the cable can be lowered without movement of the two sprocket 15 wheels.

In testimony whereof I affix my signature in presence of two witnesses.

CHRISTOPHER F. SCHLEMMMA.
